UNITED STATES PATENT OFFICE.

LOUIS E. YOAKIM, OF YUMA, ARIZONA.

VEHICLE-REACH.

1,036,051.

Specification of Letters Patent. Patented Aug. 20, 1912.

Application filed January 2, 1912. Serial No. 668,927.

To all whom it may concern:

Be it known that I, LOUIS E. YOAKIM, a citizen of the United States, residing at Yuma, in the county of Yuma and State of Arizona, have invented a new and useful Vehicle-Reach, of which the following is a specification.

This invention pertains to improvements in reaches for vehicles or wagons.

10 It has for its object, primarily, to allow for lateral careening movement of the vehicle, or wheel axles, as when a wheel, or wheels, may pass over an obstacle or drop into a rut or hole in the street or roadway, 15 without liability of twisting or splitting the reach or subjecting the hounds to torsional strain or stress.

A further object is to greatly simplify the construction of parts and accordingly 20 economize the cost of manufacture.

A still further object is to carry out the aforesaid ends in an expeditious and effective manner.

25 The invention consists of certain instrumentalities and features substantially as hereinafter fully disclosed and defined by the claim.

In the accompanying drawing, illustrating the preferred embodiment of my invention 30 wherein it will be understood that various changes and modifications may be made as relate to the detailed construction and arrangement of the parts without departing from the spirit thereof, Figure 1 is a plan 35 view of the device. Fig. 2 is a partly sectional and partly side view of the same. Fig. 3 is a transverse section produced upon the line 3—3 of Fig. 1. Fig. 4 is a like section taken on the line 4—4 of Fig. 1.

40 In carrying out my invention, I construct the reach, generally designated by the character 1, of two members or sections 2 and 3, respectively, the member 2 being preferably of wrought metal or steel and the member 45 3 being of tubular metal with an apertured flattened end portion 4, its aperture 4^a receiving a pin for connecting it to the rear axle, neither said pin nor said axle being

shown. The opposite end of the reach-member 2 terminates in an annular flange 5, the function of which will presently appear.

The reach-member 2 has an apertured flattened forward end 6, its aperture 6^a receiving the usual king-bolt; said reach-member has also two rearwardly extending divergent branches or arms 7, with their rear extremities united by a transverse portion or member 8 formed in continuation thereof. Said transverse connecting portion or member itself has an arcuate or outwardly or 60 upwardly curved formation uniting with a corresponding formation of a like transverse member 9 to form a sleeve 10, the latter transverse member being suitably bolted or riveted to the arms or branches 7 of said 65 member 2, upon their under sides.

The sleeve 10 is adapted to receive the rear flanged end of the tubular or rod reach-member, the flange thereof engaging the inner or forward edge of the sleeve to retain 70 the reach-member in position therein and yet allow of the turning or swiveling of the tubular or rod reach-member as the vehicle wheel or wheels may ride upwardly over an obstacle or may drop into a rut or hole in 75 the road-way, and thus avoid the liability of the twisting or splitting of the reach or subjecting the hounds to torsional strain or stress, as would otherwise be liable to occur. The device thus provided, is extremely simple, comprising but the minimum number 80 of parts in its organization and is inexpensive of manufacture.

What is claimed:

A device of the character described, comprising complementary reach members adapted to turn one within, and independently of the other, one reach-member being plate-like in general outline and formed with an arcuate upraised portion forming thereby a 90 concavity therein, a transverse member applied to said plate-like reach-member and having an arcuate portion with its concavity opposed to the corresponding formation of said reach-member, the other reach-member 95 being of tubular formation and having a

flange-terminal, said latter reach-member being received within the sleeve resulting from the opposition of the arcuate portions of the first-referred to reach-member and 5 said transverse member, said flange-terminal engaging one end of said sleeve.

In testimony that I claim the foregoing

as my own, I have hereto affixed my signature in the presence of two witnesses.

LOUIS E. YOAKIM.
